UNITED STATES PATENT OFFICE

GEORGE D. SHERIFFS AND CHARLES J. TRAVERS, OF MILWAUKEE,
WISCONSIN.

REVOLVING CHAIR.

SPECIFICATION forming part of Letters Patent No. 593,059, dated November 2, 1897.

Application filed January 6, 1897. Serial No. 618,183. (No model.)

To all whom it may concern:

Be it known that we, GEORGE D. SHERIFFS and CHARLES J. TRAVERS, of Milwaukee, in the county of Milwaukee and State of Wisconsin, have invented a new and useful Improvement in Revolving Chairs, of which the following is a description, reference being had to the accompanying drawings, which are a part of this specification.

10 Our invention has relation to improvements in revolving chairs of that form wherein the spindle is adapted to revolve without raising or lowering, independent means being provided for securing the vertical adjustment of 15 the spindle in order to raise or lower the chair-seat.

The object is to simplify the present forms of construction, so as to secure the above ends with the necessity of employing the fewest 20 possible number of parts, and to effect the vertical adjustment of the spindle with the least possible trouble.

In the accompanying drawings, Figure 1 is a vertical sectional view of a chair-iron embodying our invention. Fig. 2 is an inverted plan view of the chair-iron hub. Fig. 3 is a detail view of the slotted and interiorly-threaded tube. Fig. 4 is a view of the lower end of said tube. Fig. 5 is a detail view of 30 the locking mechanism, and Fig. 6 is a vertical section of a modified form of construction more especially adapted for piano-stools.

It will be understood that the invention is applicable to all forms of revolving chairs and 35 stools wherein a vertical adjustment is desirable.

In the accompanying drawings the numeral 7 indicates the chair-iron hub, which is of the usual form exteriorly, being provided with the outer recesses 8 for the reception of the ends of the chair-legs. The bore of the hub is plain and is formed near its lower end with an annular shoulder 9. Upon this shoulder is seated a clutching member 10, which consists of a collar formed with an upper beveled or outwardly-inclined end 11. Also disposed within the bore of the hub is a sleeve 12, said sleeve provided with a series of slits 13, extending from its lower end upwardly for a desired distance. Any desired number of these slits may be provided, and

we have shown four in the accompanying illustrations of the invention. The lower extremity of this sleeve is beveled or inclined inwardly, as indicated at 14, which beveled 55 or inclined extremity registers with and engages the bevel or incline 11 of the clutching-collar 10. The sleeve is provided near its upper end with a series of recesses 15. This sleeve is held against being withdrawn upwardly out of the bore of the hub by means of a ring or annulus 16, which is held rigid within the bore of the hub and bears against the upper edge of the sleeve.

The numeral 17 indicates a screw-threaded 65 spindle which carries at its upper end the spider 18, by means of which said spindle is connected to the chair-seat. This spindle enters the bore of the hub and passes through the ring or annulus 16, the sleeve 12, and the 70 clutching-collar 10, the threads of said spindle engaging the interior screw-threads of the sleeve.

The numeral 19 indicates a flat plate-spring, which is secured at one end to the outside of 75 the hub by means of the screw 20. The upper end of this spring is bifurcated, the furcate parts thereof straddling a pin 21, which pin enters an opening 22 in the hub. In order to prevent the withdrawal of the pin from its 80 opening 22, the sides of said pin just back of its head are made flat, as indicated at 23 23. The circular portion of the pin in advance of these flatsides form shoulders, with which the end of the spring contacts in case an attempt 85 is made to pull the pin out, thereby effectually preventing the withdrawal of the pin. As will be seen from Fig. 1, the upper end of the spring presses outwardly, so as to normally hold the inner end of the pin flush with the 90 inner side of the bore of the hub.

In the operation of the invention the parts are normally in the position shown in Fig. 1 of the drawings. When in this position, if the chair-seat is occupied, when said seat is rotated the spindle will be rotated therewith, as usual, and by reason of the fact that the sleeve 12 is slotted and provided with the lower beveled extremity, which is engaged by the beveled upper end of the clutching-collar, the 100 sleeve is held tightly to the spindle, so that said spindle and sleeve are revolved together.

If, now, it is desired to adjust the vertical height of the chair-seat, the pin 21 is pressed inwardly, so that its inner end engages one of the recesses 15 of the sleeve. This necessarily locks said sleeve to the hub against rotation. By now turning the chair-seat or the spindle direct said spindle is necessarily raised or lowered in accordance with the direction in which it is turned by reason of the engagement of its male threads with the female threads of the sleeve.

In the form illustrated in Fig. 6, which is more especially intended for use in connection with piano-stools, the locking-pin 21 is dispensed with entirely and the lower slotted portion of the sleeve 12 is projected outwardly somewhat to form an annular shoulder or bearing-surface 24. When the seat is unoccupied, the parts assume the position shown in Fig. 6, which illustrates the annular shoulder 24 as bearing firmly against the bore of the hub. Sufficient friction is thereby engendered between the sleeve and the hub to hold said sleeve against rotation when the screw-spindle is turned. It is therefore evident that the vertical height of said screw-spindle may be readily regulated. When, however, the seat is occupied, the weight of the person thereon will force the spindle and the sleeve downwardly, so as to wedge the registering bevels of the sleeve and the clutching-collar and permit the annular shoulder or bearing-surface 24 to just clear the surface of the hub. When the seat is then revolved, the spindle and sleeve will of course rotate together without affecting the vertical height of the spindle.

As stated at the outset, we do not wish to be understood as restricting our invention to any particular class of revolving chairs, but desire to use the features of the invention in connection with any form of revolving chair or stool. The particular formation of the hub herein shown and described, therefore, is not essential, and this may be varied to suit the particular class of chair or stool to which the invention is to be applied—as, for instance, in the case of an ordinary office stool, wherein the iron is provided with depending curved arms and a centrally-depending hub. When the invention is applied to an ordinary stool-iron of this kind, it is obvious that all the essential features of the invention are retained, notwithstanding the slight difference in the form of the hub.

What we claim as our invention is—

1. In a revolving chair, the combination, of a hub, a screw-threaded spindle extending therein, an interiorly-threaded slotted sleeve through which the screw-spindle extends, a clutch-collar engaging the slotted sleeve and adapted normally to automatically hold said sleeve to rotation with the spindle, and means for holding the sleeve against rotation to permit independent rotation of the spindle.
2. In a revolving chair, the combination, of

a hub, a screw-threaded spindle extending therein, an interiorly-threaded slotted sleeve within the hub, and through which the screw-spindle extends, a clutch-collar seated within the hub and adapted to engage the slotted sleeve, and to hold said sleeve to rotation with the spindle, and means for holding the sleeve against rotation to permit independent rotation of the sleeve.

3. In a revolving chair, the combination, of a hub, a screw-threaded spindle extending therein, an interiorly-threaded slotted sleeve through which the screw-spindle extends, said sleeve provided with a beveled portion, a clutch-collar also provided with a beveled portion registering with and engaging the bevel of the sleeve, and means for holding the sleeve against rotation to permit independent rotation of the spindle.

4. In a revolving chair, the combination, of a hub, an interiorly-threaded sleeve, a screw-threaded spindle engaging the threads of the sleeve, means for locking the sleeve to the spindle to provide for the rotation of the sleeve and the spindle together, a pin entering an opening in the hub, and a spring having one end engaging the pin to normally hold said pin out of engagement with the sleeve, said pin when pressed inwardly adapted to engage the sleeve to hold said sleeve against rotation with the spindle.

5. In a revolving chair, the combination, of a hub, an interiorly-threaded sleeve, a screw-threaded spindle engaging the threads of the sleeve, means for locking the sleeve to the spindle to provide for the rotation of the sleeve and spindle together, a headed pin entering an opening in the hub, a spring having its free end bifurcated, the furcate parts straddling the pin and engaging opposite flat sides of the pin, said pin adapted to be normally held out by the spring.

6. In a revolving chair, the combination, of a hub, a screw-threaded spindle extending therein, an interiorly-threaded slotted sleeve through which the screw-spindle extends, said sleeve provided with a beveled portion, a clutch-collar also provided with a beveled portion registering with and engaging the bevel of the sleeve, a pin entering an opening in the hub, and a spring having one end engaging the pin to normally hold the pin out, said pin when pressed inwardly against the action of the spring adapted to engage the sleeve to hold said sleeve against rotation with the spindle, and to permit independent rotation of said spindle.

In testimony whereof we affix our signatures in presence of two witnesses.
